UNITED STATES PATENT OFFICE.

ALBERT G. KOLOSA, OF NEWBERRY, MICHIGAN.

ENVELOP.

1,072,741.

Specification of Letters Patent. Patented Sept. 9, 1913.

Application filed November 30, 1912. Serial No. 734,368.

To all whom it may concern:

Be it known that I, ALBERT G. KOLOSA, a citizen of the United States, residing at Newberry, in the county of Luce and State of Michigan, have invented certain new and useful Improvements in Envelops, of which the following is a specification, reference being had to the accompanying drawings.

This invention relates to new and useful 10 improvements in envelopes and more particularly to safety envelopes.

The object of the invention is to provide an envelop embodying improved means for strengthening the construction of the envelop when sealed and also means to guard 15 against the fraudulent opening of the envelop by furnishing proof of the fact in the event that an attempt should be made to open the envelop by an unauthorized person 20 to obtain access to the contents thereof.

Another object of the invention is to provide an envelop of this character which will possess advantages in points of efficiency and durability, is inexpensive of manufacture 25 and at the same time is simple in construction and operation.

With the above and other objects in view, the invention consists in the novel features 30 of construction and the combination and arrangement of parts to be hereinafter more fully described, pointed out in the claims and shown in the accompanying drawings, in which—

Figure 1 is a plan view illustrating the 35 blank of which my improved envelop is formed. Fig. 2 is an elevation of the envelop showing the same in a partly folded position. Fig. 3 is an elevation showing the same in its closed position.

40 In the construction of my improved envelop, it will be understood that the same must be made of paper or any other suitable material and may be of any suitable size desired.

45 In the drawings, 1 indicates the body of the envelop provided with the end flaps 2 and 3, the bottom flap 4 and the top flap 5.

The flap 3 is cut inwardly upon its side edges to form angularly disposed tabs 6 50 which, when the end of the flap is disposed within the slit 7 formed in the end flap 2 will engage the body of the flap 2 at the ends of the slit to prevent the removal of the end of the flap 3 without severing the tabs 6 therefrom. The bottom flap 4 is of substantially rectangular shape and one

corner thereof is turned inwardly as shown at 8. The other corner is cut away to form the tongue 9 which is provided upon its opposite edges with the tabs 10 which, when the tongue is threaded within the slot 11 formed in the corner 8, will engage upon either end of the slit so that the tongue cannot be removed therefrom without severing the tabs.

The top flap 5 is substantially triangular in shape and is provided upon its side edges adjacent the apex thereof with outwardly projecting tongues 12, said tongues extending outwardly from the flap at diametrically opposite points and are provided at their outer ends with the angularly projecting tabs 13 which, when the tongues are engaged within the slits 14 formed in the flaps 2 and 3, will prevent the removal of 75 the tongues without severing the tabs 13. Extending outwardly from the apex of the flap 5 is a tongue 15, the outer end of which is provided with the angularly projecting tabs 16 which, when the tongue is engaged within the slit 17, formed in the flap 4, will prevent the removal of the tongue without severing the tab therefrom and from this it will be seen that it is impossible to open the envelop and gain access to the contents 80 thereof, by an unauthorized person, without furnishing proof that the envelop has been tampered with. This adds greatly to the safety of the contents of the envelop and also adds materially to the strength of the 85 connection between the various flaps of the envelop.

While I have shown and described the preferred form of my invention, it will be obvious that various changes in the details 90 of construction and in the proportions may be resorted to for successfully carrying my invention into practice without sacrificing any of the novel features or departing from the scope of the appended claims.

100 What I claim is:—

1. In a device of the character described, the combination of a body provided with end flaps, means carried by the ends of said flaps for engagement to prevent the opening 105 of said flaps without detection, a bottom flap of substantially rectangular form having one of its free corners bent inwardly and provided with a slit, the other free corner being cut away to form a tongue having 110 angular tabs formed on the opposite sides thereof and adapted to engage the ends of

the slit to prevent the removal of the tongue when inserted therein, a top flap and means carried by the top flap for engagement with the other flaps to prevent fraudulent access. 5 to the interior of the envelop.

2. In a device of the character described, the combination of a body provided with end flaps, one of said end flaps having a transverse slit, the other of said end flaps 10 being provided upon its opposite edges with recesses forming angular tabs adapted to engage the ends of said slit when the second flap is inserted therein, a bottom flap of substantially rectangular form having one 15 of its free corners bent inwardly and provided with a slit, the other free corner being cut away to form a tongue having angular tabs formed upon the opposite sides thereof and adapted to engage the other 20 corner at the ends of the slit to prevent the removal of the tongue when inserted there-

in, a top flap of substantially triangular form, oppositely disposed tongues formed upon the side edges thereof and arranged adjacent the apex, angularly disposed tabs 25 formed upon the outer ends thereof, a third tongue projecting outwardly from the apex of the top flap, angularly disposed tabs 30 formed at the outer end of the third tongue and said end flaps and the bottom flap being provided with slits to receive the tongues upon the top flap, the tabs upon said tongues preventing the removal of the tongues without severing the same from the body. 35

In testimony whereof I hereunto affix my signature in the presence of two witnesses.

ALBERT G. KOLOSA.
